UNITED STATES PATENT OFFICE.

FRED G. MAYER, OF RICHMOND, INDIANA, ASSIGNOR TO STARR PIANO COMPANY, OF RICHMOND, INDIANA, A CORPORATION OF INDIANA.

SPRING-MOTOR.

1,291,061.

Specification of Letters Patent. Patented Jan. 14, 1919.

Application filed August 31, 1918. Serial No. 252,149.

To all whom it may concern:

Be it known that I, FRED G. MAYER, a citizen of the United States, residing at Richmond, Indiana, have invented certain new and useful Improvements in Spring-Motors, of which the following is a full, clear, and exact description.

This invention is an improvement in spring motors such as are customarily used for driving the turn tables of phonographs, but applicable generally for all analogous purposes, and the primary object of the new construction is to make the spring barrel in such motors grease-tight when motor is in proper suspended position, so that under these conditions of use they will absolutely retain its lubricant, therefore insuring a smooth and quiet unwinding of the springs, also, remain perfectly clean, and free from any oil or grease on the outside of the barrel or other parts.

In the case of motors of the general character with which this application deals, it is usual to employ a mixture of graphite, oil and grease in the spring barrel or barrels, two springs in tandem being ordinarily used, in order that the springs may unwind smoothly and without noise and jumps, but no form of motor has yet been devised, or at least commercially used, in which there was any adequate provision for preventing the escape or leakage of this grease through the bearings or otherwise from the barrels. This has been a cause of great annoyance and trouble and to overcome it I have devised a form of spring motor in which the grease-containing barrels are grease-tight and free from any joints through which any such substances can find their way out.

This device is shown in the accompanying drawings in which:

Figure 1 is a view in elevation of a spring motor showing it as applied to a phonograph.

Fig. 2 is a vertical cross-sectional view of the spring barrels, and Fig. 3 is a similar view of a modification of the same parts.

In construction, operation and mode of use the apparatus differs in no essential respects from the well-known tandem spring motors now commonly used with phonographs; that is to say, there are two spring-barrels 1 and 2, with a central shaft 3, each spring being connected at one end to its barrel and at the other to the shaft. To barrel 1, which turns in or with reference to barrel 2, a gear 4 is

connected by means of which the springs are wound; and to barrel 2 a gear 5 is connected that drives the turn-table 6 of a phonograph. These parts in general construction and function being, as above stated, old and known.

My improvement consists in this: The outer or main barrel 2 I form by stamping, as shown in Fig. 2, or by casting or molding, as shown in Fig. 3, a cup, having a central hole in the bottom, if stamped, through which projects the lower end of the shaft 3, which end fits in a socket in a plate 7 of substantial thickness secured tightly to the bottom of the cup.

The under or outer side of the plate 7 is formed with a socket 8, which contains a ball-bearing, one member of which is an adjustable screw 8^a set in or passing up through the base plate 9 of the phonograph frame or support.

The outer cup 2 is united to the plate 7 and the gear 5 by screws 10, so that its rotary movement by the unwinding of the springs is imparted to the phonograph table.

In the lower part of the cup 2 the spring 11 is contained. The upper part of the cup is enlarged in diameter and contains the barrel 1 with its spring 12, and the upper and lower compartments of said cup 2 are separated by a plate 13.

The upper barrel 1 is bottomless but has a closed integral top containing only a central hole to allow of the passage of the shaft 3. The outer cup or barrel 2 is stepped and flanged at the top, and the inner or upper barrel 1 fits snugly the same and turns therein.

When the thickness of the walls of the outer barrel 2 are sufficiently thick to permit it, the inner edges of the staggered portion or shoulders at the top are formed with 45° bevels 14, Fig. 2, leaving spaces. These are designed to hold the little grease that will squeeze up during the winding up of the springs, which grease will run back into the barrels while the motor is running down, at the same time automatically lubricating the bearings between the two barrels.

By this means there is no opportunity for the leakage of any oil or grease, as the only possible avenue of escape is the joint around the shaft 3, which is prolonged by the gear 4 and other parts of the frame, besides being

at a considerable elevation above the grease which is contained in the spring barrels.

When the outer or main barrel 2 is cast in a mold, it is readily made in one piece, with a socket in its bottom for the shaft 3, as shown in Fig. 3, and the socket for the ball-bearing may also be formed in the bottom as shown. This and other details of construction, however, are not of the essence 10 of my invention, which, from the above description will be seen to reside in a closed spring barrel or barrels, with no passages to the exterior for the possible leakage of its oily or greasy contents.

What I claim is:—

15 1. A grease-tight motor comprising a central shaft and two superposed springs in tandem, in combination with an outer or main barrel with closed bottom in which the shaft is set, and an inner barrel with closed 20 top containing the upper spring and fitting and turning in the upper part of the main barrel.

2. A grease-tight motor comprising a central shaft and two superposed springs in tandem, in combination with an outer or main barrel inclosing both springs and formed with a closed bottom having a socket therein in which the shaft is set, and an inner barrel 30 containing the upper spring and having a closed top through which the shaft passes, and adapted to fit and turn in the upper part of the main barrel.

3. A grease-tight motor comprising a central shaft and two superposed springs in tandem, in combination with a main or outer barrel inclosing both springs and formed

with a closed bottom having a socket therein for the end of the shaft and a socket beneath it for a ball-bearing, and an inner barrel 40 with closed top containing the upper spring and adapted to fit and turn in the upper part of the main barrel.

4. A grease-tight motor comprising a central shaft and two superposed springs in tandem, in combination with a main or outer barrel surrounding both springs and formed in one piece with a closed bottom in which the shaft is set, and an inner barrel containing the upper spring, having a closed top 50 and adapted to fit and turn in the upper part of the main barrel.

5. A grease-tight motor comprising a central shaft and two superposed springs in tandem, in combination with a one-piece main barrel with closed bottom and the upper part of larger diameter than the lower, an inner barrel contained in the enlarged portion and surrounding the upper spring, said barrel having a closed top and fitting the upper 60 edge of the main barrel.

6. A grease tight motor, comprising a central shaft and two superposed springs in tandem, in combination with a main or outer barrel surrounding both springs and formed with a closed bottom affording a bearing for the shaft and with shoulders at its upper portion with their inner edges beveled and an inner barrel containing the upper spring, having a closed top and adapted to fit and 70 turn in the upper part of the main barrel.

In testimony whereof I hereunto affix my signature.

FRED G. MAYER.
